UNITED STATES PATENT OFFICE.

ALBERT E. NEELY, OF CHICAGO, ILLINOIS, ASSIGNOR TO W. C. RITCHIE & COMPANY,
OF CHICAGO, ILLINOIS, A CORPORATION OF ILLINOIS.

BOX AND ITS METHOD OF MANUFACTURE.

Application filed May 18, 1927. Serial No. 191,618.

My invention relates to pasteboard and similar boxes or containers and pertains more especially to receptacles of that type adapted to contain face-powder or the like and incorporating in its structure a paper or similar wall or cover designed to be broken through or ruptured to give access to the powder contents.

One aim of the invention is to provide a box of this general character which can be manufactured economically and therefore can be sold at a comparatively small price and of such structure that the powder can be filled in the box or sealed therein without difficulty, such as a partial expulsion or discharge thereof by reason of the issuing air due to its displacement by the admitted powder.

Other aims and purposes of the invention will be made apparent to those skilled in this art from an understanding of the invention, a present preferred embodiment of which has been illustrated in detail in the accompanying drawing forming a part of this specification and throughout the several views of which like reference numerals have been employed to designate the same parts.

In this drawing:

- 30 Figure 1 is a central, vertical cross-section through the complete, filled box;
- Figure 2 is a similar view of the box-cover only;
- 35 Figure 3 is a like showing of the collar or ring;
- Figure 4 presents the unfolded, circular paper sheet in central section;
- Figure 5 shows the main box body in a like manner;
- 40 Figure 6 illustrates the last three mentioned elements ready for assembly; and
- Figure 7 shows the same members united or assembled.

Referring to this drawing, it will be observed that the box or container comprises a main-body 11 having a circular or round bottom-wall 12 and a corresponding, up-standing flange or rim 13, the margin of the part 12 extending outwardly slightly beyond the companion element 13 to afford means by which such main-body may be easily grasped and held in the hand, as well as giving the container a neat and finished appearance.

55 As is clearly shown, the under face of the

bottom wall, its projecting margin, and the lower part of the exterior surface of the rim or flange are covered with a finish paper 14 which is adhered thereto, thus binding the parts together.

The element 15 is nothing more than a round sheet of paper of suitable size, being of somewhat larger diameter than that of the box rim.

Ring 16, covered on its outside with finish paper 17, has an internal diameter slightly greater than the outside diameter of the rim 13, so that it may be forced over the latter, the heights of the two parts 13 and 16 being approximately the same.

The cover 18 comprises a domed or upwardly-arched top wall 19 and its associated rim 20, both suitably exteriorly finished, usually in colors.

In practice, the box-body 11 is filled with the powder 21 as shown in Figure 6, and on this the paper disc 15 is placed concentrically, which, around the margin of its underside, that is to say around its overhanging portion, has been coated with a slight excess of adhesive, such as glue, and then the ring 16 is positioned above the paper sheet in suitable register with the underlying members.

Thereupon, such annulus 16 is forced down pressing the projecting circular part of the paper disc down into adhering contact with the outer surface of the flange 13, and squeezing out or expressing its excess glue down below the edge of such folded paper sheet, where it cements the flange 13 and the ring 16 together, the permanently united parts being then in the relations shown in Figure 7.

In thus bringing the elements together, there is no danger of any of the powder being puffed out and lost and soiling the container.

Finally, the cover 18 is applied telescopically in the customary way, the ultimate product being depicted in Figure 1.

When it is desired to use the powder, the cover is easily removed, the paper shield or holder is punctured, and the supply of powder is then available, but before the paper is thus ruptured, there is no danger of leakage of the fine powder.

Those acquainted with this art will readily understand that the invention, as defined by the appended claims, is not necessarily limited and restricted to all of the details out-

lined above, and that minor mechanical changes may be employed without departure from the substance and essence of the invention.

5. I claim:

1. The method of assembling box elements, consisting in filling the box main-body having an upstanding rim, positioning thereover an easily rupturable sheet of larger cross-
10 section with its margin extended beyond such rim, the underside of such overhanging margin having an excess of adhesive, and forcing a retaining-ring down over said rim, whereby the part of said sheet projecting beyond said
15 rim is folded down between said ring and rim and caused to adhere to the outer surface of the latter, the expressed excess of the ad-

hesive flowing down beyond the edge of such sheet and acting to cement said ring and rim together.

2. A filled box, comprising in combination, a box main-body filled with suitable material and having an upstanding rim, an easily rupturable sheet covering such filling and on top of the upper margin of the rim of said main-body and having its margin folded over the upper portion only of the outer surface of said rim and adhered thereto, and a ring fitted over said rim and such folded marginal part of said sheet and adhered to said rim below the edge of such sheet only.

In witness whereof I have hereunto set my hand.

ALBERT E. NEELY.
